INVENTOR

DeWitt Warner,
By E. J. Chapin, Atty.

UNITED STATES PATENT OFFICE.

DEWITT C. WARNER, OF CHICAGO, ILLINOIS.

IMPROVEMENT IN CHERRY-STONERS.

Specification forming part of Letters Patent No. **135,050**, dated January 21, 1873.

To all whom it may concern:

Be it known that I, DEWITT C. WARNER, of Chicago, in the county of Cook and State of Illinois, have invented a certain Improvement in Devices for Removing the Stones and Stems from Cherries; and I do declare that the following is a full and exact description thereof, which will enable those skilled in the art to make and use the same, reference being had to the drawing and letters marked thereon, herewith transmitted, and making a part of this specification.

Figure 1 is a view in perspective, showing its general construction and form, consisting of a shaft or handle, A, and three shank-like points, B B B.

This device is constructed of metal, in three parts—a loop, Fig. 2; a hook, Fig. 3; and a coil, Fig. 4, which, being adjusted with pliers, binds the loop and hook firmly together, as shown in Fig. 1, letter A.

The object of this invention or device is to afford an effective and expeditious means of

removing the stones and stems from cherries with the least crushing of the fruit, which is accomplished in the following manner;

The cherry being held by the thumb and fingers of one hand, and the device with the thumb and fingers of the other hand, the points of the instrument are inserted into the apex of the cherry, and with one movement of the hand holding the device the stone and stem are removed together.

What I claim as my invention is—

The part A bent so as to form an enlarged head, and two prongs, B, in combination with the third prong bent, as shown, to form a loop at its upper end to engage the part A, when the said parts are secured together by a wire fastening placed below the enlarged part A, as described.

DEWITT C. WARNER.
